UNITED STATES PATENT OFFICE.

JOHN GRAVES, OF GREEN POINT, ASSIGNOR TO HERMAN MILLER, OF NEW YORK, N. Y.

ASH-SIFTER.

SPECIFICATION forming part of Letters Patent No. 254,638, dated March 7, 1882.

Application filed July 23, 1881. (No model.)

To all whom it may concern:

Be it known that I, JOHN GRAVES, of Green Point, in the county of Kings and State of New York, have invented a certain new and 5 useful Improvement in Ash Receivers and Sifters, of which the following is a specification.

My invention relates to ash-receivers which have arranged within them sifters or sieves 10 into which the ashes and cinders are placed, and which are so supported that they may be partially rotated or shaken to sift the ashes through them.

The invention consists in the combination 15 of a receiver having an imperforate cover, a sifter or sieve supported therein and adapted to be turned or partially rotated, open loops or sockets which project inward from the upper edge of the sifter or sieve and serve as 20 handles whereby it may be lifted, and lugs projecting downward from the under side of the cover and engaging with said loops or sockets, whereby provision is afforded for rotating or turning the sifter or sieve by rotating 25 or turning said cover.

In the accompanying drawings, Figure 1 represents a central vertical section of a receiver and sifter embodying my invention. Fig. 2 represents a plan thereof with the cover re- 30 moved, and Fig. 3 represents an inverted plan of the cover.

Similar letters of reference designate corresponding parts in all the figures.

A designates the receiver, which may consist of a strong sheet-metal can, and which in 35 this example of my invention is strengthened by a re-enforcing band, A', at the top. The receiver is provided with handles a, whereby it may be lifted.

40 B designates an imperforate cover, likewise made of sheet metal, and provided with a downwardly-projecting rim, b, which fits inside the band A', and with handles B', which are shown as upon opposite sides of the center, and serve to lift the cover or to partly rotate or turn it upon the receiver A.

C designates the sifter or sieve, which is composed of a sheet-metal cylinder having a

perforated or reticulated bottom, C', through which the fine ashes, which will go through 50 the perforations or openings therein, are discharged. The band A' has an internal circumferential shoulder, c, and the sifter or sieve C has a flange, d, overlapping and resting upon 55 said shoulder.

In lieu of having a continuous shoulder and a continuous flange, either the receiver or the sifter might have a continuous flange, and the other having projecting lugs overlapping the same.

The flange d turns freely on the shoulder c, and permits of the sifter or sieve being partly rotated or turned to shake the ashes through the bottom C'.

The arrangement of the flange d at the top 65 or upper edge of the sifter is advantageous, as all ashes which lodge upon the shoulder c can then be brushed into the sifter, and there is no danger of ashes and cinders getting between the sifter and receiver and interfering 70 with the rotation of the sifter, as there would be if the flange d and shoulder c were at or near the bottom of the sifter.

Upon the sifter or sieve C are inwardly-projecting sockets or loops D; and E represents lugs or projecting tongues upon the under side of the cover B, which enter the sockets or loops, as clearly seen in Fig. 1, thus locking the cover and sifter or sieve together, so that the turning of one is transmitted to 80 the other. By this means the sifter or sieve C may be very easily rotated or shaken circumferentially while the cover B is on, closing the receiver tightly and preventing the escape of ashes and dust.

85 The sockets or loops D form handles whereby the sifter or sieve may be conveniently lifted and removed from the receiver.

It will be observed that after the ashes are placed in the sifter it may be operated by taking hold of the handles B' of the cover, and there is no possibility of dust and ashes escaping, as there would be if there were holes in the cover.

I am aware that an ash receiver and sifter 95 has been made in which the sifter or sieve

has attached to it rods which project upward through holes in the cover, and serve as handles for partly rotating or turning the sifter or sieve, and I therefore do not claim this as 5 my invention.

What I claim as my invention, and desire to secure by Letters Patent, is—

The combination of the receiver A, the im-
perforate cover B, the sifter or sieve C, adapt-
ed to be turned or rotated, the loops or sock-

ets D, projecting inward from the said sifter or sieve and forming convenient handles whereby it may be lifted, and the lugs E, projecting downward from the under side of said cover and engaging with said loops or sockets, all 15 substantially as herein specified.

JOHN GRAVES.
